CLAIM

The ornamental design for an electronic device as shown and described.

DESCRIPTION

This application is related to U.S. Design patent application Ser. No. 29/664,859, filed Sep. 28, 2018, now U.S. Design Pat. Ser. No. D850,446, which is a continuation of U.S. Design patent application Ser. No. 29/618,666, filed Sep. 22, 2017, now U.S. Design Pat. No. D844,607, the entire disclosures of which are hereby incorporated herein by reference.

This application is also related to U.S. Design patent application Ser. No. 29/664,867, filed Sep. 28, 2018, now U.S. Design Pat. Ser. No. D845,298, which is a continuation of U.S. Design patent application Ser. No. 29/618,666, filed Sep. 22, 2017, now U.S. Design Pat. No. D844,607, the entire disclosures of which are hereby incorporated herein by reference.

This application is also related to U.S. Design patent application Ser. No. 29/618,666, filed Sep. 22, 2017, now U.S. Design Pat. No. D844,607, the entire disclosure of which is hereby incorporated herein by reference.

FIG. 1 is a front perspective view of an electronic device showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear perspective view thereof.

The broken lines in FIGS. 1–8 show portions of the electronic device that form no part of the claimed design.

Areas encircled by broken lines, including the area encircled by the broken lines in FIGS. 3, 6, and 8 (i.e., the oval-shaped area toward the top of the electronic device and the only
